PERMANENT ELECTRIC MATCH

John Starr, Detroit, Mich.

Application August 22, 1952, Serial No. 305,874

1 Claim. (Cl. 317—89)

1

This invention relates to electric lighters, and more particularly to an electric lighter of the type wherein the ignition of a torch or match element is effected by momentarily engaging the same between two electric contacts, thereby opening and closing an electric circuit to produce a spark, said spark serving to ignite the torch or match element.

The main object of the invention is to provide a novel and improved electric lighter which is simple in construction, which is easy to use, and which may be permanently mounted in a convenient location for use whenever it is desired to ignite the match element thereof, for any purpose, such as for the lighting of cigarettes, and the like.

A further object of the invention is to provide an improved electric lighter which involves inexpensive components, which is neat in appearance, which is sturdy in construction, and which is safe to use.

Further objects and advantages of the invention will become apparent from the following description and claim, and from the accompanying drawings, wherein:

Figure 1 is a perspective view of an improved electric lighter assembly constructed in accordance with the present invention.

Figure 2 is a vertical cross sectional view taken on the line 2—2 of Figure 1.

Figure 3 is a vertical transverse cross sectional view taken on the line 3—3 of Figure 1.

Figure 4 is a horizontal cross sectional view taken on the line 4—4 of Figure 2.

Referring to the drawings, the electric lighter is designated generally at 11 and comprises a rectangular front plate 12 of insulating material, a rectangular rear plate 13 of insulating material, and bolts 14 at the respective corners of the plates, said bolts extending through said corners and through spacer sleeves 15 interposed between the plates, the bolts being provided at their rear ends with nuts 16 whereby the respective plates 12 and 13 are rigidly secured in parallel spaced relationship. Secured to the rear plate 13 in substantially parallel relationship are the opposing spaced serrated metal strips 17 and 18, the serrations of the strips being shown respectively at 19 and 20, said serrations opposing each other and being spaced apart in the manner clearly illustrated in Figure 2.

The front plate 12 is formed with a slot 21 which is in registry with the serrations 19 and 20, said slot being provided with a metal frame plate 22 on the front surface of the insulating plate 12 which reinforces the edges of the slot 21 and protect said edges against wear.

2

Secured to the rear plate 13 parallel to and spaced from the serrated strip 17 is a coil 23, said coil comprising a relatively large number of turns of wire, sufficient to provide substantial inductance for the coil, the coil being enclosed in a suitable protective housing, and the housing being clamped to the rear plate 13 by a clamping strap 24, as shown in Figures 2 and 4. One terminal of the coil 23 is connected to the metal strip 17 by a wire 25. Connected to the other terminal of the coil 23 is the line wire 26. Connected to the remaining metal strip 18 is the line wire 27. The line wires 26 and 27 are connected, by means of a suitable plug, to an electric outlet.

Secured to the front surface of the front insulating plate 12 is a vertical receptacle 28 which may contain cotton or similar porous material, as shown at 29, said porous material being saturated with a suitable volatile liquid fuel, such as benzine or the like. The container 28 is provided with the neck 30 in which is disposed the metal rod 31, said metal rod being provided at its top end with the supporting flange 32 adapted to rest on the rim of the neck 30, as shown in Figure 3, and the top end of the rod being provided with the insulating handle 33 of rubber or suitable insulating material. The lower end of the rod 31 is formed with an axial bore 34 in which is secured a wick 35 of porous material adapted to absorb the liquid fuel in the receptacle 28. As shown in Figure 3, the wick 35 projects a short distance beyond the lower end of the rod 31.

In using the device, the rod 31 is extracted from the receptacle 28 and the end thereof is inserted through the slot 21 and is moved vertically along the serrations 19 and 20, the metal portion of the rod 31 adjacent the wick 35 making intermittent contact with the serrations as the rod is moved along said serrations, whereby an electrical circuit is intermittently opened and closed, said circuit containing the coil 23, and therefore having substantial inductance. As the circuit is opened and closed, voltages of substantial magnitude are induced, causing a substantial spark to occur each time the circuit is opened and closed as the metal rod is drawn past the serrations 19 and 20. The spark ignites the wick 35, producing a flame which may be employed for lighting cigarettes, and for similar purposes. To extinguish the flame, it is merely necessary to insert the rod 31 into the vessel 28, whereby the flame is extinguished by being cut off from the source of oxygen in the atmosphere.

The rear plate 31 is provided at its top edges with the apertured angle brackets 36, 36, whereby

the device may be attached to a wall in a convenient location so that it is readily accessible for use whenever desired.

While a specific embodiment of an improved electric lighter has been disclosed in the foregoing description, it will be understood that various modifications within the spirit of the invention may occur to those skilled in the art. Therefore, it is intended that no limitations be placed on the invention except as defined by the scope of the appended claim.

What is claimed is:

In an electric lighter, a front plate of insulating material, a rear plate of insulating material, and means rigidly connecting said plates in spaced parallel relation, a pair of flat metal strips secured to said rear plate in side by side parallel, coplanar relationship, the inner edges of said strips being formed with serrations, the teeth of the serrations on one edge being staggered relative to the teeth of the serrations on the other edge, said front plate being formed with a slot registering with the serrations of said strips, a coil mounted between said plates, a first circuit

wire connected to one of the strips, a second circuit wire, said coil being connected in series between said second circuit wire and the other strip, said circuit wires being adapted to be connected to a voltage source, a receptacle mounted on said front plate, a metal rod removably supported in said receptacle, said metal rod member being formed with an axial bore at one end, and an inflammable wick secured in said bore and projecting from said one end, said wick being ignited when the rod member is moved through the slot in intermittent contact with the serrations.
